UNITED STATES PATENT OFFICE.

EVERETT P. ALLEN, OF CHICAGO, ILLINOIS; MARY A. ALLEN, EXECUTRIX OF SAID EVERETT P. ALLEN, DECEASED, ASSIGNOR TO DOLE VALVE COMPANY, OF CHICAGO, ILLINOIS, A CORPORATION OF ILLINOIS.

AIR-VALVE FOR HEATING SYSTEMS.

1,110,096.

Specification of Letters Patent.

Patented Sept. 8, 1914.

Application filed March 26, 1906. Serial No. 307,976.

To all whom it may concern:

Be it known that I, EVERETT P. ALLEN, a citizen of the United States, residing at Chicago, in the county of Cook and State of Illinois, have invented a certain new and useful Improvement in Air-Valves for Heating Systems, of which the following is a specification.

My invention relates to air valves for heating systems, and has for its object to provide a new and improved device of this description.

My invention is illustrated in the accompanying drawings, wherein—

15 Figure 1 is a view in elevation showing a device embodying my invention; Fig. 2 is a sectional view therethrough.

Like letters refer to like parts throughout the several figures.

20 My invention is adapted to be used in connection with steam heating systems, and is arranged to be connected with such a system at some suitable point, as, for example, the radiator.

25 As shown in the drawings, the present device may be said to consist of two parts A and B. The part B, which when in position is arranged so as to be acted upon by the conditions within the heating system, con-

30 sists of a movable part or diaphragm B¹ provided with an opening B² communicating with the atmosphere. This movable part is fastened to some suitable holding piece B³ which in this instance is attached to the part

35 A. The opening B² is controlled by the controlling part B⁴ which is associated with a supporting piece B⁵ preferably adjustable.

As herein shown this supporting piece consists of a screw threaded piece working in 40 screw threads in the support B⁶. This support is arranged so as not to close the passageway by means of which communication with the heating system is secured. The movable part or diaphragm B¹ is normally

45 in engagement with the controlling part B⁴ so that the opening or aperture B² is closed, and is preferably provided with a limiting device C which limits its movement so as to prevent injury in the event excessive pressure is exerted on the diaphragm.

50 I prefer to provide the parts with a protecting shell or cover C¹ which incloses them, and which is provided with an opening C² connecting the interior thereof with

the atmosphere so that any air or the like 55 passing from the system through the opening B² can escape through the opening C². The shell or cover C¹ is attached to the holding piece B³ in any desired manner, as by being soldered or brazed thereto. This holding piece forms, as it were, a diaphragm 60 chamber. The holding piece is connected with the part A by means of the projection A¹. The part A is connected with the radiator or other part of the heating system, and 65 is provided with a passageway A² leading therefrom. The part A is arranged so that the passageway A² will be open when the system starts up, or when there is air in the system which should be allowed to escape, 70 and will be closed when the steam begins to escape. Any suitable construction for this purpose may be used. As herein shown, it consists of a casing A³ forming a float chamber 75 adapted to be connected with the heating system, as, for example, the radiator, by a screw threaded connection A⁴. Within the casing is a float A⁵ provided with an engaging part A⁶ adapted to open or close the passageway A² which leads from the heating system to the part B and to the atmosphere. The float is controlled by means of 80 a suitable liquid such as water. When the water rises to a predetermined height, the float is lifted so as to close the passageway 85 and when the water is lowered the float drops so as to open the passageway. The level of the water is controlled by a pressure chamber D containing fluid such as air, and communicating with the bottom of the casing by a connection D¹.

When the system is not operating the pressure in the pressure chamber is such that there is not sufficient water in the casing A to lift the float, and hence the communication to the atmosphere will be open. The arrangement is also such that when the system is in operation and steam begins to escape, the pressure in the pressure chamber D will be increased so as to force the water 100 contained therein and in the connection D¹ into the float chamber A³ so as to lift the float and close the passageway A². This increase of pressure is caused by the heat from the heating system passing through the passageway A², as this passageway passes through the pressure chamber D. The heat heating the air or other fluid in said pres-

sure chamber causes it to expand thus forcing the water into the chamber containing the float.

The controlling part B^4 is loosely mounted upon the supporting part B^5 . As herein shown this holding part is provided with a recess in which the end of the controlling part is received, said end being preferably sharpened as shown. The other end is preferably rounded, and the opening in the diaphragm is also preferably provided with inclined faces. This makes the controlling part self-adjusting. If, for example, the diaphragm is buckled or displaced because of strain or pressure so that when it returns to its closing position the opening is somewhat displaced, the controlling part will nevertheless seat because it is free to move and adjust itself to such inequalities.

I have described a particular construction embodying my invention, but it is of course evident that the parts can be varied in many particulars, and I therefore do not limit myself to the particular construction shown.

The use and operation of my invention are as follows: When the system is first started up the air passes out through the passageway A^2 , the pressure lifting the diaphragm B^1 so that such air can escape through the openings B^2 and C^2 . When the steam begins to escape, the heat therefrom expands the fluid in the chamber D and it is forced into the casing or float chamber A^3 so as to lift the float and close the passageway A^2 . This shuts off the heat from the pressure chamber D , and as the fluid therein cools it contracts and the water or other fluid is forced from the casing or float chamber A^3 up through the connection D^1 , and when the pressure reaches a predetermined amount the level of the water will be such as to cause the float to drop and open the passageway. This action occurs intermittently and automatically so as to intermittently permit the escape of the accumulated air in the system. When the passageway A^2 is closed the pressure on the diaphragm B^1 is relieved and said diaphragm moved so as to close the opening B^2 . When the system is shut down the float A^5 drops so as to open the passageway, and the pressure being taken from diaphragm B it moves and closes the opening B^2 so as to prevent air from passing into the system. As the steam in the system now condenses a vacuum or partial vacuum is created, and this vacuum or partial vacuum is maintained because the external pressure of the atmosphere on the diaphragm B^1 keeps it closed so that the opening B^2 remains closed and hence no air can pass into the system. This vacuum is maintained in the system until it is desired to start up the steam, whereupon it will be seen that the water in the boiler

65 will be evaporated very easily and quickly

because of the vacuum, and will be rapidly carried to the various heaters and the economy and efficiency of a vacuum system thus secured.

I have used in the claims the term "compression chamber" to specify the chamber D wherein the air is compressed so as to create a pressure by means of which liquid is forced therefrom into the float chamber.

I claim—

1. A valve for steam heating systems, provided with a passageway leading to the atmosphere, a compression chamber surrounding said passageway, a diaphragm extending across said passageway and provided with an opening, a controlling part associated with said diaphragm and adapted to control said opening, said controlling part directly engaging the diaphragm and having a part in the plane thereof, the diaphragm being moved by variations in pressure in the system so as to open the communication to the atmosphere when the system is in operation and close it when the system is out of operation, so as to prevent air from entering the system and a float chamber below said compression chamber, a float in said float chamber adapted to control the passageway leading to the atmosphere, the compression chamber communicating with the float chamber below the line of flotation thereof.

2. A valve for steam heating systems, provided with a passageway connecting the system with the atmosphere, a compression chamber surrounding said passageway, a diaphragm across said passageway provided with an opening leading to the atmosphere, a controlling part loosely mounted on a support and adapted to control said opening, the diaphragm being moved to and from said part responsive to variations in pressure in the system, a float chamber below said compression chamber, a float in said float chamber, the compression chamber connecting with the float chamber below the line of flotation thereof.

3. A valve for steam heating systems comprising a casing having a conduit leading from the system to the atmosphere, two controlling devices for said conduit, one responsive to variations in heat and comprising a compression chamber surrounding said conduit, a float chamber below said compression chamber communicating therewith, a float in said float chamber provided with an engaging part adapted to close said conduit, the other responsive to variations in pressure, and comprising a diaphragm having an aperture therein, a support associated therewith, a controlling part loosely mounted in said support and toward which the diaphragm moves when the pressure in the system is relieved and which closes said aperture.

4. A valve for steam heating systems comprising a casing, a conduit leading from the system to the atmosphere through said casing, a tube inclosed in the casing and forming a part of said conduit, said tube having a controlling valve at each end thereof, a float located below said tube and controlling one end thereof, and a compression chamber surrounding said tube, a float chamber below said compression chamber in which said float is located and a connection between said compression chamber and said float chamber.
